UNITED STATES PATENT OFFICE.

GEORGE H. GILMAN, OF BOSTON, MASSACHUSETTS.

DRILLING MACHINE.

Application filed August 28, 1920. Serial No. 406,652.

My invention relates to drilling machines and particularly but not exclusively to hammer rock drills and among other things concerns a fluid pressure motor of general application.

My invention will be best understood by the following description when read in connection with the accompanying drawings which disclose a specific embodiment of my invention submitted for illustrative purposes, the scope of which will be particularly pointed out in the appended claims.

In the drawings:

Figure 1 shows a longitudinal section of a hammer rock drill embodying my invention;

Fig. 2 shows a section on the line 2—2 of Fig. 1;

Fig. 3 shows a partial section on the line 3—3 of Fig. 1;

Fig. 4 shows a section on the line 4—4 of Fig. 1; and

Fig. 5 shows a section on the line 5—5 of Fig. 2.

The submitted embodiment of my invention includes a casing comprising a cylinder member 1, a front head structure 2 and a rear head structure 3. In the cylinder is mounted for reciprocation the piston 4 provided with a hammer bar 5 extending into the front head structure. In the front head structure is rotatively mounted a chuck comprising a rearwardly extending member 6 and the forward member 7, the latter being provided with a polygonal recess for receiving the polygonal end 8 of the drill steel 9. The rearward portion of the chuck member 7 is provided with rearwardly extending lugs 10 and the forward end of the chuck portion 6 with forwardly extending lugs 11, these lugs meshing and serving to lock the chuck members 6 and 7 together so that when one is rotated the other must rotate with it. Preferably the lugs 10 and 11 are formed to permit a slight longitudinal play to compensate for inaccuracies of manufacture.

The drill steel 9 is operated by imparting thereto both percussion and rotation. For imparting the percussion to the drill steel I have herein shown, the end of the drill steel so positioned that it is struck by the end of the hammer bar at the forward end of the piston stroke, while rotative action is imparted thereto by means which will now be described.

Preferably, I rotate the chuck by motion imparted thereto by the piston. For this purpose in the submitted embodiment of my invention, the hammer bar is connected to the chuck by means of grooves and cooperating tongues or followers, providing cam surfaces and cam followers for transforming the reciprocatory motion of the piston into the rotary motion of the chuck. 60 Preferably, the grooves take the form of helical slots 15 cut in the hammer bar, while the tongues are in the form of follower lugs 16 projecting from the interior surface of the chuck and conforming to the 70 shape of the helical slots. The piston is caused to follow a predetermined path of movement and for this purpose I preferably employ the ring 12 which surrounds the hammer bar and is provided with an exterior bearing 13 in a suitable recess in the front cylinder head 14 as is clearly illustrated by Figs. 2 and 3. This ring is connected to the hammer bar by means of cooperating grooves and tongues similar to 75 those connecting the hammer bar to the chuck, the grooves preferably taking the form of straight grooves 17 cut on the exterior surface of the hammer bar, and the interior surface of the ring being provided 80 with cooperating follower lugs 18. On the exterior surface of the ring and chuck are formed ratchet teeth 19 and 20 and cooperating therewith are suitable pawls 21. The ratchet teeth on the ring and chuck are so 85 formed that each may rotate in only one and the same direction, rotation in the opposite direction being prevented by the pawls.

The operation of the parts of the submitted embodiment of my invention so far described is as follows: Assume the piston is in the position illustrated by Fig. 1 and motive fluid is admitted to drive the same rearwardly. Under these conditions the piston will move back without rotating due to its 95 inertia or because it is prevented from turning by the ring 12, it being observed that as the piston moves rearwardly, the grooves 15 and their cooperating followers 16 tend to rotate the piston and hence the ring 12 in a 100 direction contrary to that permitted by the pawls cooperating with the teeth 19 of the ring, and in consequence of this the chuck is rotated in the direction indicated by the arrow in Fig. 1 due to the cam action of the 105 surfaces of the grooves 15 upon the lugs 16 formed on the chuck. When the piston has

reached the rear end of its stroke, motive fluid admitted drives it forwardly. As the piston moves forwardly, in cases where the chuck is prevented from rotation by friction of the rock on the drill steel, the piston turns in the direction indicated by the arrow in Fig. 1. This turning action on the forward stroke of the piston results from the cam action between the grooves 15 and lugs 16, the chuck being prevented from rotating in the reverse direction in cases where the drag on the drill steel would not prevent this by means of its pawls and ratchet. When the piston reaches the front end of its stroke it is rotating rapidly, and the chuck, if it is under much load opposing rotation, as will normally be the case, will be stationary. The direction of rotation of the piston on the forward stroke is that in which it causes the chuck to rotate on the rearward stroke, and when the piston is at the point of reversal at the end of the forward stroke it is rotating most rapidly and would continue to rotate in the same direction on the rearward stroke were it not that the action of the grooves 15 and lugs 16 connecting the piston to the chuck tends to cause the piston to rotate in the opposite direction as it moves rearward, it being observed that it is this action of the grooves 15 and lugs 16 that causes the ratchet ring 12 to operate on the rearward stroke to hold the piston from rotation in the direction opposite that under consideration. The chuck therefore, through the grooves 15 and lugs 16, at or just after reversal of the piston, absorbs the rotative energy of the piston which aids the chuck in rotating. As the piston reverses in a small fraction of a second the absorbing of the rotative energy of the piston by the chuck is done almost instantly and results in a hammer blow in a rotary sense being imparted to the chuck, which is of great value when the drill tends to stick in the drill hole. It will be observed therefore that the piston on the forward stroke is caused to rotate and that when it reverses the energy of this rotation is imparted to the chuck, further rotation being imparted to the chuck due to the slip joint connections as the piston continues its rearward motion.

The rear head structure comprises a handle member 22 and the valve casing comprising the blocks 23 and 24. Formed with the valve block 24 is a motive fluid connection 25 from which leads a passage 26 adapted to be controlled by a valve for supplying the motive fluid to the opposite ends of the cylinder. Leading from the forward end of the cylinder is a passage 28 which communicates with the passage 26 through a port 29. Communicating with the rearward end of the cylinder are passages 30 which extend through the valve block member 24 and communicate with the transverse passage 31 formed in the

rearward block 23, the latter passage communicating with the passage 26 through the port 32.

The ports 29 and 32 above referred to as is clearly illustrated by the drawings are arranged in opposed spaced relation. Between the ports is mounted a valve 33 provided with opposed spherical faces 34 and 35 which are adapted to seat on the surface of the blocks about the ports 29 and 32. This valve I preferably make hollow in order to reduce its weight and inertia. Connected to the valve is a flexible stem 36 and on the end of the stem opposite the valve is secured a trunnion 37 which is preferably spherical in order to provide a universal mounting for the valve so that the latter may readily adapt itself to its seat. The blocks 23 and 24 are respectively provided with semi-spherical bearings 38 and 39 conforming to the shape of the spherical trunnion 37. The valve stem 36 is perforated at 40 and extending through such perforation is a pin 41 of smaller diameter than the perforation serving to hold the valve in operative relation to its seats. The pin 41 further serves as a dowel to hold the blocks 23 and 24 in alignment.

For exhausting the motive fluid from the opposite ends of the cylinder is a passage 42 leading to the atmosphere and communicating with the interior of the cylinder through a passage 43. The passage 43 is adapted to be uncovered by the forward and rearward ends of the piston in its reciprocation to exhaust the motive fluid from in front and behind the piston.

The operation of the valve mechanism is as follows: Assume the motive fluid supply is in communication with the connection 25: Under these conditions, if the parts are in the position illustrated by Fig. 2, the motive fluid is flowing into the rear end of the cylinder through the port 32 and passages 31 and 30. This has driven the piston from its rearward to its forward end and with the position of the piston as shown, the motive fluid is discharging to the atmosphere through the passage 42 and the motive fluid which has been trapped in the forward end of the piston is exerting pressure on the spherical face 34 of the valve. The discharge of motive fluid to the exhaust through the passage 42 relieves the pressure on the rearward face 35 of the valve which permits the pressure acting on the opposite face 34 to shift the valve to the rear, closing the port 32 and opening the port 29. The motive fluid now flows through the port 29 and passage 28 to the forward end of the cylinder, the motive fluid in the rear end of the cylinder continuing to exhaust through the passage 42. This moves the piston rearwardly. After the piston in its rearward stroke closes the passage 43, it traps and

compresses fluid in front of it and this fluid acting through the passages 30 and 31 on the rearward face 35 of the valve tends to balance the pressure exerted on the forward face 34 of the valve and as soon as the forward edge of the piston uncovers the port 43 and exhaust fluid from behind it to the atmosphere, the pressure on the surface 34 of the valve is relieved sufficiently to allow the pressure on the opposite surface 35 to throw the valve again to the position shown by Fig. 2. The operation is now repeated.

In order that the piston may operate the drill steel by impact and rotation, the latter is held in operative relation to the piston and chuck by means of a suitable tool retainer. This retainer comprises a yoke portion 44 adapted to engage the collar 45 of the drill steel and formed therewith are the rearwardly extending members 47 and 48. The portion 47 of the retainer is bent to form the trunnion 49 and the portion 48 bent to form a similar trunnion 58. Extending rearwardly from the portion forming the trunnion 58 is a portion 59 bent to form a suitable handle member 60. For supporting the trunnions of the yoke I preferably form the ends of the side rods 61 and 62 with eyes 63, the rod forming the yoke being bent on arcs of sufficient radius to allow the yoke to be threaded through the eye of the side rod adjacent the handle of the yoke.

The portions of the front head adjacent the eyes are cut away to form the shoulders 65 and 66, conforming to the shape of the eyed portions of the side rods and thus holding the eyes in aligned relation and preventing the side rods from turning.

To lock the handle in position I provide at the side of the casing forming the front head structure, lugs 67 and 67', the portion between the lugs being recessed as at 68 to conform with the exterior surface of the handle. As the handle is resilient when the same is forced over the member 66, it snaps into engagement with the recess 68 which holds the handle from moving from position until it is forcibly removed from the recesses. In order to prevent harmful vibration of the yoke, which would tend to cause wear in the eyes and trunnions I preferably form the lugs 67 and 67' and the recess 68 so that the handle portion 69 is continually under flexure. This provides a resilient means which tilts the yoke and causes it to bind in the eyes, the trunnion 58 binding against the surface A of the eye and the trunnion 49 against the surface B.

The side rods 61 and 62 extend rearwardly of the casing and project from the handle member where they are provided with nuts 70, the cylinder member and head structure being provided with openings to receive the bolts and the walls of these openings being

contracted at the portions 71, 72, 73, 74 and 75 thereof to tightly engage the bolts in order that the latter may act as dowels to hold the parts in assembled angular relation.

The pawls 21 hereinbefore referred to are provided with hub portions 76 surrounding the side bolts. A double bearing for the pawls is provided by permitting the exterior surface 77 of the hub to bear on the casing and the interior surface 78 to bear on the side 75 bolts. It will be understood in devices of this character, the pawls are subject to considerable wear and by thus arranging the parts, the bearing surfaces of the pawls are considerably increased and their life pro- 80 longed.

It will be observed that I have provided a machine in which the casing containing the mechanism for operating the drill steel and the mechanism for retaining the drill steel 85 in position to be so operated are all held in assembled relation by means of the side bolts.

Although I have described one specific embodiment of my invention for illustrative purposes, it is to be understood that I am 90 not limited thereto and that extensive deviations may be made therefrom without departing from the spirit of my invention.

Claims:—

1. A drilling machine having in combination, a casing, a hammer piston in said casing, a chuck mounted for rotation in said casing, means for rotating said piston on its strokes in one direction without enforcing rotation of said chuck and imparting the energy of such rotation to said chuck after completion of said strokes, and means causing said piston to enforce rotation of said chuck on its strokes in the opposite direction.

2. A drilling machine having in combination, a casing containing a reciprocatory hammer piston, a chuck mounted for rotation relatively to said casing, a slip joint connection between said piston and chuck, a member having a slip joint connection with said piston and a ratchet connection with said casing permitting said piston to rotate in the same direction as said chuck, said slip joint connections each comprising a cam the pitch of the cam of one relatively to the pitch of the cam of the other causing said piston on one stroke to rotate in the same direction as that in which said chuck rotates but without said piston enforcing rotation of said chuck and on the next stroke causing said piston to enforce rotation of said chuck after imparting its energy of rotation to said chuck.

3. A drilling machine having in combination, a casing containing a reciprocatory 125 hammer piston, a chuck mounted for rotation relatively to said casing and having a ratchet connection with said casing, a slip joint connection between said piston and chuck, a member having a slip joint con-

connection with said piston and a ratchet connection with said casing permitting said piston to rotate in the same direction as said chuck, said slip joint connections each comprising a cam the pitch of the cam of one relatively to the pitch of the cam of the other causing said piston on one stroke to rotate in the same direction as that in which said chuck rotates but without said piston enforcing rotation of said chuck and on the next stroke causing said piston to enforce rotation of said chuck after imparting its energy of rotation to said chuck.

4. In a drilling machine, a casing, a reciprocating piston in said casing having a hammer bar provided with straight and helical grooves lying side by side, a chuck in said casing having a slip connection with said helical groove, ratchet teeth formed on the exterior of the rear end of said chuck, a ring surrounding said hammer bar and abutting the rear end of said chuck, said ring having a slip connection with said straight groove, pawls cooperating with the ratchet teeth on said chuck and ring for permitting rotation of said ring and chuck in but one and the same direction, whereby on one stroke said piston imparts rotation to said chuck without itself rotating and on the subsequent stroke said piston rotates in the same direction as that in which it has imparted rotation to said chuck.

5. In a drilling machine, a drill steel, a casing, a reciprocating piston in said casing having a hammer bar provided with straight and helical grooves lying side by side, a chuck carrying said drill steel rotatably mounted in said casing and having a slip connection with said helical groove, a ring surrounding said hammer bar rearwardly of said chuck and having a slip connection with said straight groove, and means for permitting said ring to rotate in but one direction, whereby on one stroke said piston imparts rotation to said chuck without itself rotating and on the subsequent stroke said piston rotates in the same direction as that in which it has imparted rotation to said chuck.

6. In a drilling machine, a casing, a drill steel, a chuck rotatably mounted in said casing and carrying said drill steel, a piston in said casing and having a hammer bar, helical grooves on said hammer bar in engagement with cooperating lugs on said chuck, an angularly moving member, means permitting said member to rotate in but one direction, and a slip joint connection between said member and piston causing one to rotate when the other rotates, whereby said piston and said chuck may rotate alternately on opposite strokes of said piston and said piston on alternate strokes causes the rotation of said chuck.

7. In a drilling machine, a cylinder, a piston therein having a hammer bar, a

chuck, an angularly movable member disposed between said cylinder and chuck, means providing a slip connection between said hammer bar and said member, means providing a slip connection between said hammer bar and said chuck and including a cam surface oblique to the axis of the piston and hammer bar, and means permitting rotation of said member and hammer bar in only one and the same direction and preventing rotation thereof in the opposite direction, whereby said piston on one stroke rotates without rotating said chuck and on its stroke in the opposite direction without itself rotating causes said chuck to rotate in the same direction as that in which said piston rotated on the preceding stroke.

8. In a drilling machine, a cylinder, a piston therein having a hammer bar, a chuck, an angularly movable member disposed between said cylinder and chuck, means providing a slip connection between said hammer bar and said member, means providing a slip connection between said hammer bar and said chuck and including a cam surface oblique to the axis of the piston and hammer bar, and separate means permitting rotation of said member and hammer bar in only one and the same direction and preventing rotation in the opposite direction, whereby said piston on one stroke rotates without rotating said chuck and on its stroke in the opposite direction causes said chuck to rotate.

9. In a drilling machine, a cylinder, a piston therein having a hammer bar, a ratchet ring surrounding said hammer bar, a chuck receiving said hammer bar, straight grooves on said hammer bar cooperating with said ring, helical grooves on said hammer bar cooperating with said chuck, ratchet teeth on said chuck, and pawls cooperating with said ring and chuck ratchet teeth for preventing rotation of said ring and chuck in one direction, whereby on one stroke said piston imparts rotation to said chuck in one direction without itself rotating and on the subsequent stroke said piston rotates in the same direction as that in which said chuck is rotated.

10. In a drilling machine, a cylinder, front and rear head structures therefor, side bolts providing a common means engaging both head structures and extending the length of said cylinder for securing said head structures to said cylinder, a drill steel, means for rotating said steel comprising a ratchet, and a pawl cooperating with said ratchet and surrounding one of said side bolts.

11. In a drilling machine, a cylinder, a head structure therefor, a drill steel, a piston for imparting percussion to said steel, mechanism operated by said piston for rotating said steel, said mechanism including

a pawl, means for retaining said steel in operative relation to said piston to have imparted thereto such percussion and to be rotated, and a bolt providing a common means 5 for directly holding said cylinder, said head structure, said pawl and said means for retaining the steel in assembled relation.

12. In a drilling machine, a cylinder, a head structure therefor, a drill steel, a piston 10 ton for imparting percussion to said steel, mechanism operated by said piston for rotating said steel, means for retaining said steel in operative relation to said piston to have imparted thereto such percussion and 15 to be rotated, a bolt for directly holding said cylinder, said head structure, and said means for retaining the steel in assembled relation, and a pawl cooperating with said mechanism and surrounding said bolt.

13. In a rock drill, a cylinder, a rear head 20 structure, a chuck, a chuck casing, a drill steel carried by said chuck, a hammer piston in said cylinder for operating said steel, mechanism operated by said piston for rotating said chuck and steel including a 25 ratchet and pawl, a retainer for holding said steel in said chuck against the action of said piston, bolts extending the length of said cylinder for holding said rear head and chuck casing in assembled relation with said 30 cylinder, said pawl surrounding one of said bolts, said bolts having heads in the form of eyes adjacent said chuck casing, and said retainer being pivotally carried in said eyes.

In testimony whereof, I have signed my 35 name to this specification.

GEORGE H. GILMAN.
